(57) **CLAIM**

The ornamental design for a part of a baby carrier, as shown and described.

DESCRIPTION

FIG. 1 is a front perspective view of a part of a baby carrier showing our new design,

FIG. 2 is a rear perspective view thereof,

FIG. 3 is a front thereof,

FIG. 4 is a rear view thereof,

FIG. 5 is a left side view thereof, the opposite side being a mirror image,

FIG. 6 is a top view thereof,

FIG. 7 is a bottom view thereof,

FIG. 8 is a front perspective view of a second embodiment of the part of a baby carrier,

FIG. 9 is a rear perspective view thereof,

FIG. 10 is a front view thereof,

FIG. 11 is a rear view thereof,

FIG. 12 is a left side view thereof, the opposite side being a mirror image,

FIG. 13 is a top view thereof, and,

FIG. 14 is a bottom view thereof.

In the drawings, the dotted broken lines depict portions of the article that form no part of the claimed design; the dashed broken lines represent claimed stitching on the article.

Different textures of the first and second embodiments of the article are represented by different surface ornamentation.

1 Claim, 14 Drawing Sheets
